UNITED STATES PATENT OFFICE.

CHARLES A. YALE AND CHARLES E. YALE, OF BURLINGTON, VERMONT, ASSIGNEES TO
YALE WONDER CLOCK COMPANY, OF BURLINGTON, VERMONT, A CORPORATION
OF VERMONT.

ADVERTISING APPARATUS.

No. 878,171.

Specification of Letters Patent.

Patented Feb. 4, 1908.

Application filed October 9, 1906. Serial No. 338,165.

To all whom it may concern:

Be it known that we, CHARLES A. YALE and CHARLES E. YALE, citizens of the United States, both residing at Burlington, in the county of Chittenden and State of Vermont, have invented certain new and useful Improvements in Advertising Apparatus, of which the following is a specification.

Our invention relates to advertising apparatus, and is especially designed for use in show windows and other conspicuous or suitable places.

The prime object of this invention is to provide improved mechanism for so manipulating and automatically displaying a sign, portrait, tablet or advertisement that it will be visible a predetermined length of time.

Another object is to provide mechanism for this purpose which will readily move heavy signs or pictures made on glass or any other desirable material in an easy and uniform manner so that each will be displayed long enough to read the sign or picture.

Another object is to provide simple mechanism for automatically projecting or reflecting a colored light or shade on each picture or sign as it is moved or presented to the sight by the sign or picture moving means.

A further object is to provide longitudinal and transverse anti-friction run-ways, whereby heavy signs or pictures or both are readily manipulated both in a longitudinal and transverse direction.

The foregoing and such other objects as may occur from the ensuing description are attained by the mechanism illustrated in the accompanying drawings, in which—

Figure 1 represents a plan view of the mechanism embodying our invention, each of the longitudinal top rails of the frame being shown as partly broken away to illustrate the longitudinal run-ways. Fig. 2 is a side elevation of the apparatus showing the framework broken away in parts. Fig. 3 is a detail view of the mechanism employed for moving the colored glasses or reflecting surfaces. Fig. 4 is an inverted detail plan view of a portion of the apparatus, and Fig. 5 is a detail view of the means employed for locking the sliding or reciprocating rods.

The main wheel A is secured to the upper end of the driving shaft B, the latter being mounted vertically in the framework and adapted to be revolved by any desirable means, preferably by an electric motor, not shown in the drawings.

The framework of the apparatus may be made of any suitable material, preferably of metal and being substantially rectangular in shape or contour, it comprises namely, four upright posts or standards 1, one at each corner, upper and lower longitudinal beams 2, a central longitudinal tie or strengthening beam 3, and transverse beams 3'.

As will be seen by reference to Fig. 1, the two lower longitudinal beams and the transverse beams a are channeled or recessed to receive anti-friction rollers b, to form an anti-friction surface for the sign, pictures or cards, whereby those made of heavy material may be readily moved in both a longitudinal and transverse direction.

A number of teeth 4 are formed on the periphery of the wheel A, said teeth extending only partially around said wheel. Sliding rack-bars 5 are arranged opposite each other and are each connected to or formed with a guide frame 6 formed with depending members 7 at each side and end thereof, said members carrying rollers 8 mounted so as to roll or move back and forth on the rods 9 secured to the frame at each side thereof. The rack-bars 5 are at all times arranged and located opposite each other (as shown in Fig. 1) as the guide frame 6 to which said rack-bars are connected is rigidly held intact by the cross braces 10.

Rigidly secured to the underside of the main wheel A, is a cam 12 (see Fig. 5), which is adapted to contact with the roller carried at the inner end of each of the reciprocating or sliding rods 13, said rods being designed to actuate pusher-arms 14, said arms being formed with bosses 15, fixed to vertical shafts 16, mounted one at each diagonally opposite corner of the frame. The shafts 16 are rocked or vibrated by means of levers or arms 17, one end of each of which is provided with a downward projected portion 18 pivotally secured to the end portion of the rods 13. Each of the pusher-arms 14 is pro-

vided with adjustable fingers or pusher-pins 18^X, adapted to move in and out of the frame.

Each of the rods 13, is mounted in and guided by projections 19, secured to the central longitudinal beam of the frame, and a portion of each rod is surrounded with a spiral spring 20, and a stop 21. At the inner end portion of each of said rods 13 is secured a roller *c* and said rod is provided with a recess *c'*, the latter being designed to receive a locking pawl 22 pivotally secured to beam 3 and provided with a coiled spring 23, adapted to retain the locking pawl within said recess *c'* until it is automatically released.

15 As will be seen by reference to Figs. 4 and 5 of the drawings, the underside of the main wheel is provided with a cam 24, adjustably mounted in a slot in said wheel by a set screw 24^X and said cam as the main wheel A is revolved, will at the proper time, contact with and depress the outer end of the pawl 22 thus releasing said pawl from the recess *c'*.

20 The automatically operated mechanism for projecting or reflecting a colored light or shade on each sign or picture at the proper time will now be described. Projecting from the front of and rigidly secured to the upper longitudinal beam of the frame are provided three rigid extensions or supports 26, the central one of which carries a shaft 27, and to each end of said shaft is secured a disk 28 to which is suitably fastened near the periphery thereof, a series of sockets 28^X of any desirable construction each socket 30 adapted to receive and retain one end of a colored piece of glass 29. Opposite each disk 28 and at a suitable distance therefrom is a similar disk provided with sockets to receive the other end of the colored piece of 35 glass. These pieces of glass are so arranged as to form a space within which is placed an incandescent light (shown by dotted lines in Fig. 1) connected with any suitable source of 40 electricity.

45 Connected to or supported by the frame at the central portion thereof, is an upright shaft 30, provided at its lower end with an arm 31 and at its upper end with an arm 32 to which is secured one end of a coiled spring 50 32^X, the other end being connected to the frame. Carried by the upper structure of the frame is a shaft 33, one end of which is connected to arm 32 and the other end leading to and connected with a slotted arm 34 carrying a spring pawl 35. The hub portion of the arm 34 is provided with a ratchet wheel 36 and is secured to the shaft 27. The arm 31 on the lower end of the shaft 30 is adapted to contact at the proper time, with 55 a projection 37 on one of the members of the guide frame 6, whereby through the operation of the mechanism shown in Fig. 3, the colored lights are successively rotated and

adapted to be reflected on the face of the picture or sign as it is being displayed. 65

Two series of pictures, advertising signs or cards 40^X are placed within the frame in position end to end on the transverse anti-friction run-ways above the wheel A, and the pictures or signs are actuated to slide or roll along the longitudinal run-ways from right to left to be brought into view serially one after the other at the front of the frame at the left hand side. 70

75 Referring to Fig. 1, the mechanism moves one picture toward the right in front along the front longitudinal runway, and while that picture is being viewed, one picture at the back of the right hand column is moved toward the left along the rear longitudinal runway, 80 and so on alternately. The adjustable pusher-pins 18^X carried by the pusher-arms 14 are designed to push the right hand column supported on the transverse runways toward the back and the left hand column toward the 85 front, alternately, and at intervals between the sliding or rolling movements. By this action the number of pictures in each column may be equalized, and each presented to view in serial order. 90

95 Referring to the mechanism for moving or sliding the pictures, it will be seen that each of the guide frames 6, are provided with an upright 40 to the upper portion of which is fixed a pin or bar 41 partially surrounded by a coiled spring 42, one end of the latter being connected to said upright and the other end to a bar or finger-plate 43 pivotally secured to said pin 41, said bar being adapted to spring into a position to engage the end frame 100 of a picture or sign to slide it toward the opposite end of the frame.

105 The operation of the apparatus may be described as follows: As the wheel A is rotated in the direction of the arrow in Fig. 1, the rack bars 5 and guide frames 6 are carried toward the right in said figure, and the upright 40 and bar or plate 43 move a picture along the front longitudinal anti-friction runway from left to right, the pusher-arms 14 and pusher-pins carried thereby being swung outward until the picture has completed its movement, and then returning to the original position push the right hand column of pictures to the rear. At the same time 110 the front picture is being moved from left to right in the frame by the front upright bar, the rear upright bar is being moved along the rear longitudinal runway from the left to the right hand and caused to 115 assume such position as will move the rear picture in the right hand column from right to left, when the shifting mechanism is moved in the last named direction, since both the longitudinally moving or shifting mechanism 120 and the pushing means at the front and rear

of the apparatus are substantially the same in construction and operation. As the wheel A revolves the cam 12 secured to the underside thereof contacts with the rollers c forcing the rods 13 outward which in turn causes the pusher-arms 14 to move inward. The outward movement of the rod causes the coiled spring 20 to be compressed and when the recess c registers with the locking pawl

10 22, said pawl will engage the said recess thus locking the rod 13 until the cam 24 secured to the underside of the wheel A depresses the outer end of said pawl thereby disengaging the rod 13 and permitting the

15 15 spring 20 to force the rod inward which movement in turn forces the pusher-arms outward.

It will be understood that the colored light displaying mechanism is automatically operated and caused to make a step by step movement by reason of the projection 37 on one of the members of the guide frame 6, said projection engaging with the arm 31 on the lower end of the shaft 30, whereby different colored lights or shades are displayed on the

25 front or face of the picture or sign.

From the foregoing description it will be obvious that all the pictures in both columns are successively displayed in rotation. It will also be noted that each picture is moved

30 in four different directions in its cycle of movement.

Various changes in the detail construction of our invention may be resorted to without departing from the spirit or scope of the invention as defined in the appended claims.

Having thus described our invention what we claim and desire to secure by Letters Patent is:—

1. An apparatus of the character described, comprising a frame, a wheel, reciprocating mechanism carried by said frame and operated by said wheel, pusher-arms supported by the frame, and mechanism secured to the said frame engaging the reciprocating mechanism and operated thereby for displaying different colored lights.

2. An advertising apparatus including a frame, a wheel, reciprocating mechanism operated by said wheel, upright pusher-bars carried by said reciprocating mechanism, pusher-arms carried by the frame, sliding rods adapted to operate the pusher-arms, and means carried by the frame and said wheel for locking and unlocking said sliding rods.

55 3. An apparatus of the character described comprising a frame, a wheel, racks operated by said wheel and caused to travel in unison, pusher-arms, and sliding rods for rocking the pusher-arms back and forth.

60 4. An apparatus of the character described comprising a frame, a wheel, mechanism reciprocated by said wheel, a cam secured to the wheel, sliding rods operated by

said cam, and means for locking and unlocking said sliding rods.

65

5. An apparatus of the character described, including a frame, a wheel, reciprocating mechanism supported by said frame and operated by said wheel, and means engaging with said reciprocating mechanism and operated thereby for displaying a different colored light or shade at intervals.

6. An apparatus of the character described, including a frame, a wheel, reciprocating mechanism operated by the wheel, pusher-arms provided with adjustable pusher-pins and sliding rods operated by said wheel, said rods being adapted to operate the pusher-arms.

7. An apparatus of the character described including a frame, a wheel, reciprocating mechanism operated by said wheel for moving a picture or sign back and forth, a cam secured to said wheel, pusher-arms, and sliding rods operated by said cam, each of said rods being connected at its outer end to an arm adapted to operate the pusher-arms.

8. An apparatus of the character described, including a frame, a wheel, reciprocating mechanism operated by said wheel, 90 sliding rods, a cam carried by the wheel for moving said rods, locking means for the rods, and a cam secured to said wheel for unlocking said locking means.

9. An apparatus of the character described, comprising a frame, a wheel, reciprocating mechanism operated by the wheel, said reciprocating mechanism having an upright, a hinged pusher-bar secured to said upright, pusher-arms carried by the frame, 100 sliding rods adapted to operate said pusher-arms, and means carried by the reciprocating mechanism for operating a light displaying mechanism.

10. An apparatus of the character described comprising a frame, means for causing mechanism to be reciprocated on said frame, reciprocating mechanism carrying upright pusher-bars, pusher-arms, sliding rods for operating said pusher-arms, and means for 110 locking and unlocking said rods.

11. An apparatus of the character described including a frame, longitudinal and transverse anti-friction runways secured to the frame, reciprocating mechanism carried 115 by said frame, and means for moving said reciprocating mechanism.

12. An apparatus of the character described including a frame, longitudinal and transverse runways, a driven-wheel, sliding 120 rods, means for locking and unlocking said rods, and means secured to said wheel for operating the rods.

13. In an advertising apparatus, a frame, a gear wheel, reciprocating mechanism operated by said wheel, a light displaying device,

sliding rods, means for locking the rods, a cam for unlocking the sliding rods, pusher-arms connected to and operated by said rods, and a projection on the reciprocating mechanism engaging with and operating said displaying device.

14. In an advertising apparatus, a milled gear, rack bars moved thereby, reciprocating rods, a cam for reciprocating the rods, 10 and longitudinal and transverse runways supported by the frame, said runways being

provided with series of anti-friction rollers, substantially as described.
